Primary Examiner — Christian P. McLean*Assistant Examiner* — Ava Etemadi(74) *Attorney, Agent, or Firm* — K&L Gates LLP(57) **CLAIM**

The ornamental design for a display screen with a graphical user interface as shown and described.

DESCRIPTION

The sole FIGURE is a front view of a display screen with a graphical user interface, showing our new design. The outer edge of the display screen is understood to be congruent with the outer edge of the graphical user interface. The broken lines illustrate portions of the graphical user interface that form no part of the claimed design.
